OR D 785

N° 785.

H. Smith & J. A. Sheldon
Design for Stove Plate

Patented. April 22, 1856

Res. 785

Harvey Smith and Fredk: A. Sheldon, of Troy, N.Y.
Letters Patent No. 785, Dated April 22, 1856

The Schedule referred to in these Letters Patent, and
making part of the same.

To whom it may concern:

Be it known, that we Harvey
Smith and Frederick A. Sheldon, of the City of
Troy and County of Rensselaer in the state of New
York, have invented or produced a new design to be
cast upon stove plates, and do hereby declare, that
the following is a full and exact description of the
character which distinguishes it from all other things
before known, particular reference being had to the
accompanying drawings, making a part of these
specifications.

The center of this ornament or design
is a convex button head incircled by a concave ring
immediately surrounded by a projecting narrow
flat ring or circle ornamented around by small
button head drops, forming a center from which extend
in every direction, congegated rays, every attenuate
one of which being cut short forms a brilliant circle
or star center, the other rays gradually widening to
such extent as the plate upon which it is cast may
require and terminating at the ends with a beveled
congegated finish corresponding with the surface.

Having thus fully described our
design, what we claim therein as new and
for which we desire to secure Letters Patent is
the foregoing design and configuration forming

424

Des. 785

an ornamental design for stove plates as illustrated
by the drawings
